UNITED STATES PATENT OFFICE.

GREENLEAF WHITTIER PICKARD, OF AMESBURY, MASSACHUSETTS.

OSCILLATION-DETECTING MEANS FOR RECEIVING INTELLIGENCE COMMUNICATED BY ELECTRIC WAVES.

No. 904,222.

Specification of Letters Patent.

Patented Nov. 17, 1908.

Application filed March 11, 1907. Serial No. 361,659.

To all whom it may concern:

Be it known that I, GREENLEAF WHITTIER PICKARD, a citizen of the United States of America, and a resident of the town of Amesbury, State of Massachusetts, have invented certain new and useful Improvements in Oscillation - Detecting Means for Receiving Intelligence Communicated by Electric Waves, the principles of which are set forth in the following specification and accompanying drawing, which disclose the form of the invention which I now consider to be the best of the various forms in which said principles may be embodied.

This invention relates to oscillation detecting means for receiving intelligence communicated by electric waves, as by wireless telegraphy or telephony.

The object of the invention is to obtain a detector of the thermo-electric regenerative class disclosed in my Patent No. 836,581 of November 20, 1906, with all the accompanying advantages, which shall in addition have permanent operativeness in being capable of absolutely permanent operating adjustment. Detectors of this class comprise two massive electrical conductors coöperatively having high thermo-electric power, and in contact, but mechanically distinct, to establish a high resistance thermo-junction, the electrical contact being good at the high resistance junction, and the massive conductors having low resistance circuit contacts. These conductors are massive, in the sense that their structural dimensions are not such as will offer a sufficient resistance to the oscillating currents, to materially dissipate their energy in the form of heat in the mass of the conductors themselves, before the currents can effectively reach the high resistance junction. Such massive conductors are thereby (*i. e.*, by not having essential structural limitations) distinguished from conductors which are artificially attenuated to produce high ohmic resistance, and from those conductors which naturally have the attenuated form, as of a crystal, accompanied by high ohmic resistance due to structure and not to specific resistance. The differentiated conductors of high structural ohmic resistance are not suitable for use in this invention, because that resistance causes a dissipation of the oscillating current energy in the mass of the conductors themselves, thus

not permitting sufficient energy to reach and heat a thermo-junction to a practically operative degree.

The invention consists of the novel subject matter hereinafter described with reference to the accompanying drawing, and specified in the appended claims.

The drawing is a vertical section of the best embodiment of the invention which I have yet produced.

The invention will be described with particular reference to one particular combination of conductor - materials which I have found to give the best results.

In the drawing the massive members are shown at Y and P, in contact at T J to establish the thermo-junction of high resistance. The massive member Y is composed of the sulfid molybdenite, which is the mineral ore and chemical compound with sulfur of the metal molybdenum. This compound is of no value as an element of a detector unless it is employed in accordance with this invention. But it possesses properties peculiarly adapted for use in a detector of the massive thermo-electric regenerator class, when so employed. These properties are not possessed by either of its constituents, the metal molybdenum, and the element sulfur, the former of which is an excellent conductor of electricity resembling iron, while the latter is one of the best non-conductors of electricity and could therefore not be used as an element of a thermo-electric regenerator. Sulfur in nowise resembles molybdenite, of which it forms the major part. The compound molybdenite is a soft or yielding and flexible non-metallic substance, normally an imperfect conductor of electricity, and is markedly graphitic in appearance and in its ability to make marks on paper, and is therefore sometimes mistaken for graphite. In addition to its high specific resistance as a non-metallic substance, it has a different kind of resistance, which is dealt with in this invention.

This compound molybdenite, together with another suitable massive conductor, coöperatively having high thermo-electric power, and in surface contact with each other to establish a high resistance junction, and with means for pressing the two together to merely establish a good contact at the junction, these being all the usual requirement-

of detectors of this general class, will not constitute an operative detector. I have discovered the reason for this, and have provided a remedy, which not only produces a 5 detector which is operative, but one which is substantially as sensitive as the silicon detector of my Patent No. 836,531 of November 20, 1906.

The essential for detectors of this general 10 class is a high-resistance, good-contact, thermo-junction between massive, mechanically-distinct couple members co-operatively having high thermo-electric power. Theoretically, therefore, molybdenite should be an 15 efficient massive member, but I found that practically it was not, when subjected to the ordinary conditions applicable to detectors of the general class. The means by which the compound is made not only a useful element 20 of an operative detector, but an essential part of a most sensitive device, are shown in the drawing. Here the molybdenite member Y, covered by a piece of copper foil C, rests on the flat surface of a hard 25 rubber support or sleeve R, and engages the upper end of the yieldingly mounted conducting pin P, which is the other massive member and extends through the perforation of the part R, to establish a high resistance 30 thermo-junction with the member Y. The copper foil C may have soldered to it a lead 1 to one side of the circuit which may be any suitable one, such as that of my said Patent No. 836,531. A second part of hard 35 rubber Q rests on top of the copper foil C. All the parts R, C, Y, Q and B are held 40 in a U-shaped clamping frame F. A screw A extends through this clamp F and bears on the brass plate B. A spring S forces up 45 the massive member P to make a good contact at the high resistance junction T J, the pressure averaging about two ounces.

In trying to work with molybdenite, I was 5 unable, in the lack of the above described structure, to obtain results. The pressure obtained at the junction as by employing a spring against one massive member, which was sufficient to produce good results with other substances, I found to be ineffectual 10 with molybdenite; notwithstanding that the pressure was sufficient to obtain a very good electrical contact at the junction, owing to the softness of the compound. It appeared at first indeed, as if this very character of softness, which caused a large area of junction 15 surface with even a slight pressure, permitted a junction of too low resistance to provide an efficient detector. But I observed that the true reason for this peculiar state 20 of affairs was not because the compound had insufficient resistance to be useful in contributing toward the production of a high resistance junction, and not because the junction area was too large or of too low resistance; but because the compound itself en-

masse had a resistance which was not too low, but which was on the contrary too high. I then discovered that the normal excessively high resistance of the mass Y was apparently due to its laminar structure, the 70 laminæ being not in good electrical contact with each other; the normal excessive resistance of the mass in series with the thermo-junction preventing any effective action, either by preventing the oscillating currents from acting on the thermo-junction so as to be converted into heat, or by preventing the effective flow of any direct current generated by a possible production of heat, or by wasting the energy by the generation 80 of heat in the mass. The mechanical structure above described constitutes means for obviating this defect, because when the screw A is set very tightly down on the plate B, so as to subject the molybdenite to a comparatively great pressure, sometimes as great as ten pounds, the condition of the device is altered from inoperativeness to a state of perfect operativeness and extraordinary 85 sensitiveness. When the molybdenite is put 90 under this comparatively great pressure, apparently the laminæ are jammed into good electrical contact with each other, thus reducing the normally excessive resistance of the device to such an extent as to permit 95 the passage of sufficient electrical energy through the effective thermo-junction T J to generate sufficient heat to produce and permit sufficient direct current flow to 100 operate the telephone.

The clamping frame F furnishes a suitable means of applying the high pressure required, which generally could not be conveniently accomplished in a compact structure by means of a spring. The sleeve R is 105 of insulating material because it is in contact with the member Y, and subjected to the high pressure engagement therewith at all times. With different samples of molybdenite, the optimum pressure apparently 110 does not vary, being usually about ten pounds. The other member of the device, the pin P, may be of aluminum, the oxid film of which contributes to the high resistance of the junction T J. But I have found 115 that a pin tipped with bismuth, as by soldering, as shown at M, gives better and more dependable results with molybdenite, in that this combination apparently possesses higher thermo-electric power. When Y is 120 of molybdenite, the conductor P may, however, be of any metal, almost any metal sulfid or conducting chemical compound, any non-metal or any metalloid; and likewise when Y is an equivalent of molybdenite.

The metallic spring S, which presses the pin P comparatively gently (one or two ounces) against the member Y, is held in place by the screw T, which is adjustable by the constructor to secure the permanent 130

optimum pressure. After the constructor has adjusted the clamp and spring to the optimum pressure for a given combination, the entire device should be sealed in a small box with suitable circuit terminals, in order that the user may not alter that optimum adjustment. When the pin P is held by only slight pressure against the conductor Y, such that it does not sink to some extent into the latter, sufficiently to hold it rigidly in place, it is better to closely confine the pin in the perforation in the insulator R; in order to prevent relative angular or lateral movements of the conductors which might vary the optimum pressure at the junction, a binding post D may be provided in the frame F for the other circuit lead 2.

A peculiar feature of the member Y, is its adaptability for use in this combination, notwithstanding its soft or yielding nature. The member P, when in the form of a pin, and forced by the pressure of spring S against the member Y which is under the clamp-impression, will have its rounded end slightly sunk into the mass Y, without cutting or shearing the mass, so as to greatly increase the apparent junction-area, without decreasing, but on the contrary, increasing, the useful operative effect. The molybdenite is so soft that it yields, even when subjected to such comparatively slight junction-pressure as will not make it operative in this invention. This fact might seem to indicate that its inoperativeness under slight pressure, producing apparently large contact area, was due to too great contact area, and consequent too low junction-resistance. But this is not true, as above explained; Inasmuch as the operativeness is comparatively independent of apparent contact-junction area, the member P need not be in the form of a pin having a sharp or needle point, but may have a considerable surface in contact with Y, such as would be constituted by a rounded end of member P as shown in the drawing. Other materials, which do not possess this property of softness, cannot be subjected to sufficient pressure to thereby alone have a stable mechanical adjustment, without causing such reduction of the junction resistance as to impair operativeness.

It is necessary, not only that the effective thermo-junction T J be a good contact of high resistance, but that the connection of the massive-members to the circuit be good contacts having relatively low resistance in order that the useful action will be confined to the junction T J. The structure herein disclosed produces these results, in that the clamp and spring not only respectively produce a suitable high resistance and good contact at T J, but insure a good low resistance large-area contact between Y and C and a low-resistance contact between P and S, these being the means by which the massive-mem-

bers are connected in circuit. The contact between P and S, two low resistance conductors, need not be of large area, but it is sufficient if it be of low resistance relative to T J. The contact between Y and C should 70 not only be of low resistance, but of large area, in order that any possible generation of Joulean heat at this contact between the metal C and the high resistance material Y, shall be distributed through so relatively 75 large a mass of material that the resulting temperature rise will be negligible relative to that at T J. In any case, the physical shapes of the conducting massive-members are not material to the invention, except in- 80 sofar as concerns the production of the proper junction T J.

The detector of this invention is nearly as sensitive as the most sensitive detector heretofore known, and permits much sharper 85 tuning, owing to the fact that this device is a pure ohmic resistance, practically devoid of asymmetric capacity which would interfere with tuning in the oscillation circuit. It is also the most stable detector I have ever 90 used. It has withstood the most severe static discharges without the slightest resulting effect upon its sensitiveness, these discharges being frequently applied at an intensity twenty thousand times as great as that of the 95 received signals. The device should not, however be left in any wise connected with sending circuits, as the heat generated by the powerful currents therefrom, might be sufficient to weld together the separate massive- 100 members and thus break down the high resistance of the contact-junction.

I claim:

1. Oscillation-detecting means for receiving intelligence communicated by electric 105 waves, which comprises two massive and mechanically distinct electrical conductors coöperatively having high thermo-electric power and in good electrical contact with each other, one of said conductors being non-metallic and having high specific resistance; one of said conductors possessing an excessive resistance in series with the junction; and means for reducing said excessive resistance to permit effective action by the received oscillations resulting from the transmission of the intelligence by electric waves.

2. Oscillation-detecting means for receiving intelligence communicated by electric waves, which comprises two massive electrical conductors coöperatively having high thermo-electric power and in contact with each other, said conductors being mechanically distinct, and one being non-metallic and having high specific resistance, to establish a high resistance junction; one of said conductors possessing an excessive resistance in series with the junction; means for reducing said excessive resistance to permit effective action by the received oscillations 130

- resulting from the transmission of intelligence by electric waves; and means for pressing the conductors together to establish a good contact at the junction.
5. 3. Oscillation-detecting means for receiving intelligence communicated by electric waves, which comprises two massive electrical conductors coöperatively having high thermo-electric power and in contact with each other, said conductors being mechanically distinct, and one being non-metallic and having high specific resistance, to establish a high resistance junction; one of said conductors being a soft yielding chemical compound, and the other being relatively harder; and means for pressing said conductors together to cause the harder conductor to sink into the softer conductor and establish an electrically good and mechanically stable contact at the high resistance junction.
4. Oscillation-detecting means for receiving intelligence communicated by electric waves, which comprises two massive electrical conductors coöperatively having high thermo-electric power, and in good contact with each other, said conductors being mechanically distinct, and one being non-metallic and having high specific resistance, to establish a high resistance junction; one of said conductors being a chemical compound having excessively high structural resistance which is reducible by the application of pressure; and means for compressing said compound to eliminate its excessive resistance and produce effective high resistance.
5. Oscillation-detecting means for receiving intelligence communicated by electric waves, which comprises two massive electrical conductors coöperatively having high thermoelectric power, and in contact with each other, said conductors being mechanically distinct, and one of said conductors having high specific resistance, to establish a high resistance junction; one of said conductors having a laminar structure in which the laminae are in imperfect electrical contact; and means for pressing said laminae into good contact with each other.
50. 6. Oscillation-detecting means for receiving intelligence communicated by electric waves, which comprises two massive electrical conductors coöperatively having high thermo-electric power and in good electrical contact with each other, said conductors being mechanically distinct, and one of said conductors being non-metallic and having high specific resistance, to establish a high resistance junction; one of said conductors having an excessive structural high resistance, and means for obviating the deleterious effect of the excess of resistance.
7. Oscillation-detecting means for receiving intelligence communicated by electric waves, which comprises two massive elec-
- trical conductors coöperatively having high thermo-electric power and in good contact with each other, said conductors being mechanically distinct, and one being non-metallic and having high specific resistance, to establish a high resistance junction; one of said conductors being a relatively soft substance of high structural resistance which is reducible by the application of pressure; and means for compressing said compound to reduce its resistance to an effective degree.
8. Oscillation-detecting means for receiving intelligence communicated by electric waves, which comprises two massive electrical conductors coöperatively having high thermo-electric power and in good contact with each other, said conductors being mechanically distinct, and one being non-metallic and having high specific resistance, to establish a high resistance junction; one of said conductors having a relatively soft and laminar structure of high ohmic resistance which is reducible by the application of pressure; and means for compressing said conductor to reduce the laminæ resistance and produce effective high resistance.
9. Oscillation-detecting means for receiving intelligence communicated by electric waves, which comprises two massive electrical conductors coöperatively having high thermo-electric power and in good electrical contact with each other, said conductors being mechanically distinct, and one being non-metallic and having high specific resistance, to establish a high resistance junction; one of said conductors possessing an excessive structural resistance in series with the junction; and a clamp to compress said high resistance conductor and reduce its resistance.
10. Oscillation-detecting means for receiving intelligence communicated by electric waves, which comprises two massive electrical conductors coöperatively having high thermo-electric power and in contact with each other, said conductors being mechanically distinct, and one being non-metallic and having high specific resistance, to establish a high resistance junction; one of said conductors possessing excessive structural resistance in series with the junction; a clamp to compress said excessive resistance conductor to reduce its resistance; and a spring for pressing said conductors together to establish a good contact at the high resistance junction.
11. Oscillation-detecting means for receiving intelligence communicated by electric waves, which comprises two massive electrical conductors coöperatively having high thermo-electric power and in good electrical contact with each other, said conductors being mechanically distinct, and one being non-metallic and having high specific resistance, to establish a high resistance junction; one of said conductors possessing an excess-

sive structural resistance in series with the junction; and means for compressing said high resistance conductor to reduce its resistance to an operative degree.

- 5 12. Oscillation-detecting means for receiving intelligence communicated by electric waves, which comprises two massive electrical conductors coöperatively having high thermo-electric power and in contact with 10 each other, said conductors being mechanically distinct, and one being non-metallic and having high specific resistance, to establish a high resistance junction; one of said conductors being a mass of a soft chemical compound, and the other conductor being a pin of a relatively harder material; and means for pressing said members together to establish an electrically and mechanically stable contact at the high resistance junction.
- 20 13. Oscillation-detecting means for receiving intelligence communicated by electric waves, which comprises two massive electrical conductors coöperatively having high thermo-electric power and in good electrical 25 contact with each other, but mechanically distinct, to establish a high resistance junction; one of said conductors being molybdenite, having excessive resistance between its laminæ; and means for compressing the 30 molybdenite to reduce its resistance to an operative degree.

14. Oscillation-detecting means for receiving intelligence communicated by electric waves, which comprises two massive electrical conductors coöperatively having high thermo-electric power and in contact with each other, but mechanically distinct, to establish a high resistance junction, one of said conductors being the chemical compound 35 pound molybdenite, and the other being the metal bismuth; and means for compressing the molybdenite to reduce its resistance to an operative degree; said conductors being in good contact with each other at their high 40 resistance junction, and having low resistance circuit contacts.

15. Oscillation-detecting means for receiving intelligence communicated by electric waves, which comprises two massive electrical conductors coöperatively having high thermo-electric power, and in contact with each other, but mechanically distinct, to establish a high resistance junction, one of said conductors being a chemical compound 50 of a non-metal and a metal; and means for establishing a good electrical contact at the high resistance junction of said conductors, low resistance circuit contacts for said conductors.

60 16. Oscillation-detecting means for receiving intelligence communicated by electric waves, which comprises two massive electrical conductors coöperatively having high thermo-electric power and in contact with 65 each other, but mechanically distinct, to es-

tablish a high resistance junction, one of said conductors being a chemical compound of a non-metallic substance and a metallic substance; and means for establishing good electrical contact at the high resistance junction of said conductors, and low resistance circuit contacts for said conductors.

70 17. Oscillation-detecting means for receiving intelligence communicated by electric waves, which comprises two massive electrical conductors coöperatively having high thermo-electric power and in contact with each other, but mechanically distinct, to establish a high resistance junction, one of said conductors being a chemical compound of a metal with the non-metal sulfur; and means for establishing good electrical contact at the high resistance junction of said conductors, and low resistance circuit contacts for said conductors.

75 18. Oscillation-detecting means for receiving intelligence communicated by electric waves, which comprises two massive electrical conductors coöperatively having high thermo-electric power and in good electrical 80 contact with each other, but mechanically distinct, to establish a high resistance junction, one of said conductors being a relatively soft high resistance chemical compound of a non-metal with a metal; and means for establishing good electrical contact at the high 85 resistance junction of said conductors, and low resistance circuit contacts for said conductors.

90 19. Oscillation-detecting means for receiving intelligence communicated by electric waves, which comprises two massive electrical conductors coöperatively having high thermo-electric power and in good electrical contact with each other, but mechanically 95 distinct, to establish a high resistance junction, one of said conductors being a soft chemical compound of a non-metallic substance with a metallic substance; and means for establishing good electrical contact at the high 100 resistance junction of said conductors, and low resistance circuit contacts for said conductors.

105 20. Oscillation-detecting means for receiving intelligence communicated by electric waves, which comprises two massive electrical conductors coöperatively having high thermo-electric power and in good electrical contact with each other, but mechanically 110 distinct, to establish a high resistance junction, one of said conductors being a high resistance compound of a non-metallic substance with a metallic substance; and means for establishing good electrical contact at the high 115 resistance junction of said conductors, and low resistance circuit contacts for said conductors.

120 21. Oscillation-detecting means for receiving intelligence communicated by electric waves, which comprises two massive elec- 130

- trical conductors coöperatively having high thermo-electric power, and in electrical contact, but mechanically distinct, to establish a high resistance junction; said conductors 5 having low resistance circuit contacts; said conductors having a material relative difference in the property of hardness; an insulating support having a perforation containing one of the conductors, said support resting 10 against the other conductor; the conductor in the perforated support being longer than the support; and means for pressing through the perforation and against the other conductor, the conductor contained in the perforation, to cause the harder conductor to sink 15 into the softer conductor.
22. Oscillation-detecting means for receiving intelligence communicated by electric waves, which comprises two massive electrical conductors coöperatively having high thermo-electric power, and in electrical contact, but mechanically distinct, to establish a high resistance junction; said conductors having low resistance circuit contacts; two 20 supports bearing on opposite sides of one conductor, one of the supports being of insulating material perforated to receive the other conductor and permit it to engage the first conductor; and means for clamping the first conductor between said supports.
23. A means for converting the energy of the feeble oscillating currents produced by intelligence-transmitting electro-magnetic waves, into a form suitable for operating 35 direct-current indicating instruments, which comprises two substantially non-attenuated and substantially non-commutated conducting contact members, one of which consists of a chemical combination of a metallic element with a non-metallic element, said chemical combination possessing the ability, when operatively in substantially perfect electrical contact with the other contact member, to furnish a direct current from the 40 energy of the applied oscillating current.
24. A means for converting the feeble oscillating currents produced by intelligence-transmitting electro-magnetic waves, into a form suitable for operating direct-current 45 indicating instruments, which comprises two substantially non-attenuated conducting contact members, one of which consists of a chemical combination of a chemical element with at least one other chemical element, 50 said chemical combination possessing the ability, when operatively in substantially 55

perfect electrical contact with the other contact member, to furnish a direct current from the energy of the applied oscillating current.

60

25. A rectifier for small oscillatory currents consisting of a compound of molybdenum and sulfur.

65

26. A rectifier for small oscillatory currents consisting of sulfid of molybdenum.

27. A rectifier for small oscillatory currents consisting of molybdenite.

70

28. A receiver for wireless telegraphy systems consisting of a compound of molybdenum and sulfur in contact with electrodes.

75

29. A rectifier for small oscillatory currents consisting of molybdenite in contact with electrodes.

30. A receiver for wireless telegraphy systems consisting of molybdenite in contact with electrodes.

80

31. A receiver for wireless telegraphy systems consisting of a sheet of molybdenite, and electrodes engaging opposite sides of the sheet.

32. A means for converting the energy of the feeble oscillating currents produced by intelligence-transmitting electro-magnetic waves, into a form suitable for operating direct-current indicating instruments, which comprises two substantially non-attenuated and substantially non-commutated conducting contact members, one of which possesses the ability, when operatively in substantially perfect electrical contact with the other contact member, to furnish a direct current from the energy of the applied oscillating current.

85

33. A means for converting the energy of the feeble oscillating currents produced by intelligence-transmitting electro-magnetic waves, into a form suitable for operating direct-current indicating instruments, which comprises two substantially non-attenuated and substantially non-commutated conducting contact members, one of which consists of a chemical combination of a metal with at

95

least one other chemical element, said chemical combination possessing the ability, when operatively in substantially perfect electrical contact with the other contact member, to furnish a direct current from the energy of the applied oscillating current.
